MERCHANDISE DISPLAY SIGN

Arthur E. Molke, Minneapolis, Minn., assignor to Pacific Gamble Robinson Company, Minneapolis, Minn., a corporation of Delaware

Application September 10, 1956, Serial No. 42,878

Term of patent 7 years

(Cl. D1—12)

Fig. 1 is a front elevational view of a merchandise display sign, showing my new design;

Fig. 2 is a view in side elevation as seen from the left to the right with respect to Figure 1; and

Fig. 3 is an ornamental design for a merchandise display sign, substantially on the line 3—3 of Fig. 1.

I claim:

The ornamental design for a merchandise display sign, as shown.
